[57] **CLAIM**

The ornamental design for a portable two-way radio or similar article, as shown and described.

DESCRIPTION

FIG. 1 is a top, front and left side perspective view of a portable two-way radio or similar article showing my new design;

FIG. 2 is a right side elevational view thereof;

FIG. 3 is a rear elevational view thereof;

FIG. 4 is a top plan view thereof;

FIG. 5 is a bottom plan view thereof; and

FIG. 6 is a top, front and left side perspective view of a second embodiment of the control unit illustrated in FIG. 1.

The right side, rear and bottom of the embodiment disclosed in FIG. 6 are identical to the corresponding views of the embodiment disclosed in FIG. 1.

The broken line showing of the antenna is for illustrative purposes only and forms no part of the claimed design.

Fig. 1
